CLAMP DRAW GUN

Filed Oct. 13, 1927

UNITED STATES PATENT OFFICE.

ANTHONY A. TANCREDI, OF LONG ISLAND CITY, NEW YORK.

CLAMP-DRAW GUN.

Application filed October 13, 1927. Serial No. 225,982.

This invention relates to a gun, motor or means for drawing wire or other clamp into secure engagement with spliced parts of garden hose or the like.

5 It is aimed to provide a novel tool capable of operation by means of compressed air or other power fluid.

It is further aimed to provide a novel construction wherein the cylinder is adapted 10 to be secured to one end of the clamp and the piston rod of the device is adapted to be secured to the other end of the clamp.

15 The more specific objects and advantages will either be pointed out or become apparent from a consideration of the description following taken in connection with accompanying drawing illustrating an operative embodiment.

In said drawing:

20 Figure 1 is a view in longitudinal central section illustrating the improved apparatus;

Figure 2 is a front elevation of the apparatus;

25 Figure 3 is a plan view illustrating the clamp as drawn about a spliced joint in accordance with my invention;

Figure 4 is a modified form of joint in connection with which the device is used, and

30 Figure 5 is a sectional view taken on the line 5—5 of Figure 4.

Referring specifically to the drawing, 10 designates a cylinder to which a base 11 is screwed at one end as at 12. At the other 35 end, a bonnet 13 is applied which is clamped in place by a ring 14 screwed to the cylinder as at 15.

Slidable within the cylinder 10 is a suitable piston head 16 carried by a piston rod 40 17 which projects through an opening 18 in an end closure or cap 19 threaded as at 20 to the outer end of the bonnet. An expansive coil spring 21 surrounds the rod 17 and bears at one end against the piston head 16 and 45 at the other end against the inner end of the bonnet 13.

Compressed air or other power medium is adapted to be admitted to the cylinder 10 between the piston and base 11 as through a 50 passageway 22 to which a valve 23 communicates and which controls the admission of compressed air or other power medium or fluid. A pet cock or outlet valve 24 is provided for the exhaust of power fluid from 55 the cylinder 10 and of course is normally closed.

The device is used to draw a wire clamp such as that shown at 25 in Figures 3 and 4, around sections of rubber or flexible garden hose 26, being spliced together and which 60 ends are disposed over a short length of pipe or the like 27. The clamp 25 is generally of U-shape and is a wire strand whose terminals 28 are passed through the loop formed by the device and bear against the 65 bridge 29 of the clamp. Such bridge 29 is adapted to be detachably engaged by the rod 17 and for instance by a hook 30 at the free end of such rod. The terminals 28 are adapted to be clamped to the cap 19. To 70 this end, the cap is provided with spaced ears 31 between and to which a clamping lever 32 is pivoted by a pin at 33. Lever 32 may have a lug at 34 adapted to bind against the terminals 28 and the flexed portions thereof into a notch 35 in the cap 19, in line therewith. Appropriate pressure is applied to the lever 32 at the lug 34 through the operation of a screw 36, which is threaded through an opening 37 in such lever. 80 The screw extends through a slot 39 in bonnet 13 and at its inner end bears on the rod 17 and in the operation of the parts is adapted to be engaged by a cam bar 38 rigidly secured to the rod 17.

85 In one form of the invention as in Figure 3, the clamp is drawn taut with portions thereof engaging adjoining ends of the sections 26 while in the form of Figure 4, a complete clamp is optionally used, with each 90 of the sections 26.

In using the device, with the same connected as in Figure 1, and pet cock 24 closed, valve 23 is opened and compressed air is admitted to passageway 22 into the cylinder 95 10, forcing the cylinder 10 to the left, thus drawing the terminals 28, causing the clamp to tightly engage the hose sections 26 and bind them against the metal pipe end 27. During such relative movement of the piston 100 and cylinder 10, the set screw 36 rides on the cam 38 which serves to effectively maintain the lever 32 in binding engagement with the terminals 28. In order to release the compressed air from the cylinder 10, the pet 105 cock 24 is opened. The spring 21 then restores the cylinder and piston into normal relation so that the same will disengage bridge 29 and terminals 28, after which the excess terminals 28 may be removed by 110 pincers or the like to form a completed joint as in Figures 4 and 5.

Various changes may be resorted to provided they fall within the spirit and scope of the invention.

I claim as my invention:—

- 5 A device of the class described comprising a cylinder provided with a bonnet, a cap on said bonnet, a piston within the cylinder, a rod extending from the piston and slidable through the cap, said rod having a cam thereon, an expansive spring engaging the piston and said bonnet, means for admission

10 of operating fluid to the cylinder, said bonnet having a slot, a hook on said rod to engage a portion of a clamp, ears on said cap, a lever pivoted to said ears and engageable with another portion of the clamp, a screw carried by the lever and extending through said slot into the bonnet for coacting engagement with said cam. ¹⁵

In testimony whereof I affix my signature.

ANTHONY A. TANCREDI.
